[57] CLAIM

The ornamental design for a bird feeder, as shown and described.

DESCRIPTION

FIG. 1 is a front elevational view of a bird feeder showing my new design;

FIG. 2 is a rear elevational view thereof;

FIG. 3 is a right side elevational view thereof, the left side being a mirror image of the right side shown;

FIG. 4 is a top plan view thereof;

FIG. 5 is a bottom plan view thereof;

FIG. 6 is a front elevational view of a modified form of the bird feeder shown in FIG. 1;

FIG. 7 is a rear elevational view of FIG. 6;

FIG. 8 is a right side elevational view of FIG. 6, the left side being a mirror image of the right side shown;

FIG. 9 is a front elevational view of a second modified form of the bird feeder shown in FIG. 1;

FIG. 10 is a rear elevational view of FIG. 9; and

FIG. 11 is a right side elevational view of FIG. 9, the left side being a mirror image of the right side shown. The top and bottom of the modified forms are the same as the top and bottom shown in FIGS. 4 and 5, respectively.

FIG. 1

FIG. 3

FIG. 2

FIG. 5

FIG. 4

FIG. 6

FIG. 9

FIG. 8

FIG. 11

FIG. 7

FIG. 10
